Primary Examiner — Cynthia Underwood*(74) Attorney, Agent, or Firm* — Thomas J. Oppold; Larkin Hoffman Daly & Lindgren Ltd.**CLAIM**

The ornamental design for a cable crimp cover, as shown and described.

DESCRIPTION

FIG. 1 is a top end perspective view of the cable crimp cover of the present design.

FIG. 2 is a front elevation view of the cable crimp cover of FIG. 1.

FIG. 3 is a rear elevation view of the cable crimp cover of FIG. 1.

FIG. 4 is a right side elevation view of the cable crimp cover of FIG. 1.

FIG. 5 is a left side elevation view of the cable crimp cover of FIG. 1.

FIG. 6 is a top plan view of the cable crimp cover of FIG. 1.

FIG. 7 is a bottom plan view of the cable crimp cover of FIG. 1; and,

FIG. 8 is a front elevation view of the cable crimp cover of FIG. 1 in relation to a cable (shown in broken lines).

The broken lines illustrate environmental structure and form no part of the claimed design.
